UNITED STATES PATENT OFFICE.

LEWIS M. KELLOGG, OF LOS ANGELES, CALIFORNIA.

AIRCRAFT CONSTRUCTION.

Application filed March 19, 1925. Serial No. 16,739.

To all whom it may concern:

Be it known that I, LEWIS M. KELLOGG, a citizen of the United States, residing at Los Angeles, in the county of Los Angeles and State of California, have invented new and useful Improvements in Aircraft Constructions, of which the following is a specification.

My invention relates to improvements in 10 dirigible air craft of the Zeppelin type, the objects being, first, to construct a dirigible craft wholly by the use of a wood frame work and covered with a wood covering. A second object being to provide in an air 15 craft of the type named a practical method of construction which will show strength, stiffness and resistance to fatigue due to longitudinal, transverse and circumferential stresses. A third object being to provide a 20 covering that will develop a very low degree of skin friction, and fourth to develop a craft of the type named in which the excessively long longitudinal metal frame is replaced by a frame of wood whereby the craft 25 while in flight may not become a favorable conductor for the passage of a static charge of electricity from a zone of high pressure to one of low pressure.

In the construction of the latest example 30 of air craft of the Zeppelin type a wall comprising the body member of the craft, enclosing the gas bags, is built up of a system of longérons and bracing made of "duralumin" and covered with canvas. The length 35 of such craft is usually 6 to 7 times its diameter and the wall in some instances is about 10 feet thick. In building such a craft in the manner and of the materials herein set forth the entire structure is composed of 40 wood, preferably spruce, and in the accompanying drawings are shown fragments of the wall, so composed, in longitudinal and transverse section.

With reference to the drawings:

Fig. 1 is a transverse fragmentary view 45 of the wall of a dirigible air craft showing a wood covering and a bracing therefor.

Fig. 2 is an enlarged fragmentary view of the material forming the covering and in 50 some places the bracing which supports it.

Fig. 3 is an enlarged fragmentary view of the covering and showing a method of using the same material for a brace element.

Fig. 4 is an enlarged fragmentary view of the covering and showing a second method 55 of using the same material as a brace element.

Fig. 5 shows in longitudinal section a fragment of the structure shown transversely in Fig. 1, the view being taken on line A, A 60 Fig. 1.

Fig. 6 is an enlarged longitudinal view of a brace element shown in Fig. 5 and showing how a brace can be light-weighted by cutting out certain portions. 65

Fig. 7 is a transverse fragmentary view of the wall showing a different method of bracing than that shown in Fig. 1.

Fig. 8 is an enlarged longitudinal fragmentary view of the structure shown transversely in Fig. 7. 70

In the construction of the dirigible air craft herein set forth the material used for the covering and largely the bracing, for the present purposes, may be designated as 75 woven ply wood, a sample of which is submitted herewith. With reference to Figs. 2 and 8, the facing sheets of this woven ply wood are formed of wood ribbons shaved from stock pieces and having a thickness, 80 according to the strength desired in the finished material, ranging from .015 to .030 of an inch. Such ribbons comprise the warp and weft in a special loom which forms them into a simple weave as shown. In the weaving waterproof glue is wiped upon the warp so that the finished weave is glued in the lap 85 of the warp and weft ribbons.

To build up the woven ply wood a sheet of the weave is laid down and corrugations 90 made from the same wood ribbons are glued upon it, using water-proof glue. A second sheet of the weave is then glued upon the corrugated filler. Such material has great strength and stiffness between wide points of 95 support. It can be made into sheets having a width as great as 8 feet and a length of 20 feet or more, and when properly joined at the edges a continuous sheet of the material can be made. The material thus formed is 100

impervious to water. The material because of its stiffness and strength can, when properly fixed at the ends, be used as brace elements.

In order to obtain the necessary longitudinal stiffness in a craft of the sizes such craft is usually built, three longitudinal tubular members may be constructed of the woven ply wood which may be stiffened transversely by woven ply wood or other braces as shown in the fragmentary views 1 and 5 or 7 and 8.

In Fig. 1 (see also Fig. 5) numeral 1 indicates an outer longitudinal tubular member forming a covering. 2 indicates an intermediate tubular member and 3 indicates an inner tubular member within which gas bags may be placed, all being formed of the woven ply wood continuous and unbroken from end to end and circumferentially, the ends of the craft being drawn to points as is the common practice with such structures. Longérons 4 and 5 are glued to the members 1 and 2 respectively and between each pair of longérons a sheet 6 of the woven ply wood is set in glue; also on the surfaces of the tubular members 2 and 3 are glued longérons 7 and 8 respectively and between each pair of longérons is fixed a radial brace 9 formed of the woven ply wood. This construction is further strengthened by the use of the continuous zigzag brace members 10 connected to alternate longérons 4 and alternate longérons 5 and a like brace member 11 connected to alternate longérons 7 and alternate longérons 8. These continuous zigzag brace members may be formed of a lamina of thin strips of spruce glued together and which extend circumferentially in an unbroken unit.

Referring again to Fig. 1 in such a structure the longérons 4, 5, 7 and 8 might be omitted and the weight and strength of material represented in them might be transferred into the tubular members 1, 2 and 3 by making the woven ply wood a little heavier in the facing sheets and deeper in the corrugation. Also the continuous zigzag brace elements 10 might be replaced by a brace formed of sheets of the woven ply wood.

Such a structure is shown in Figs. 7 and 8 in which the woven ply wood brace element between the tubular members 1 and 2 is numbered 12 and that between members 2 and 3 is numbered 13. These brace elements 12 and 13 represent big unbroken discs and stiffen the entire structure circumferentially. The brace elements may be fixed to the tubular members in various ways, one method being shown in Fig. 8 in which the brace sheets 12 and 13 are connected to the tubular members by gluing in corner pieces 14, 14. Such a method of joining a brace sheet to the member braced

gives a strong wide hold on the two pieces.

In Fig. 3 is shown a fragment 15 upon which is glued a longéron 16 having a central member 17 extending out far enough to form a tongue upon each side of which is glued the facing sheets of the woven ply wood brace element 18.

In Fig. 4 is shown a fragment 19 of the covering upon which is glued a longéron 20 having a sheet 20^a of the woven ply wood glued on each side, thus developing a double brace element. The structures shown in Figs. 3 and 4 illustrate methods by which the brace elements 6 and 9 may be fixed to the longérons 4, 5 and 7, 8 of the structure shown in Fig. 1.

In Fig. 2 is shown in a top view two sheets of the woven ply wood joined together by a strip of wood 21. In Fig. 8 is shown such a joint in elevation. In joining two sheets together in this manner the corrugated filler is cut back far enough to allow for the insertion of the strip 21. These strips may be composed of three ply of spruce two ply of which may run across the joint and the third ply with it.

For the reason that the longitudinal tubular members should not be broken nor the circumferential brace elements, it would not be practical to provide a man way along the bottom of the craft within the wall, like that provided in the conventional Zeppelin type of craft; therefore for a craft such as that herein set forth a man way should be constructed in a narrow car, depending from and formed integral with the craft on its under side and extending throughout its entire length.

It is to be understood that the number of longitudinal tubular members and the exact disposition of the brace elements which strengthen and stiffen the tubular members as set forth, forms no part of my present invention, and that many changes might be made in the invention as shown without departing from the spirit thereof as claimed.

Having thus described my invention, I claim:

1. An air craft of the type named, having a body member composed of a plurality of tubular members formed of the woven ply wood and brace elements disposed so as to stiffen and support the tubular members.

2. In an air craft of the type named, a body member composed of a plurality of tubular members formed of the woven ply wood and spaced apart and brace elements inserted between the tubular members adapted to stiffen them and support them circumferentially.

3. In an aircraft of the type named, a body member composed of a plurality of tubular members formed of the woven ply wood and spaced apart and brace elements formed of the woven ply wood inserted be-

tween and fixed to the tubular members adapted to stiffen their surfaces and support them circumferentially.

4. In an air craft of the type named, a body member composed of a covering formed of the woven ply wood and brace elements disposed within the circumference

formed by the covering for strengthening it longitudinally, stiffening its surface and supporting it transversely and circum- 10 ferentially.

In testimony whereof I have signed my name to this specification.

LEWIS M. KELLOGG.
